UNITED STATES PATENT OFFICE

2,613,830

LIFT TRUCK FORK

Louie H. Ponnequin, Honolulu,
Territory of Hawaii

Application March 15, 1948, Serial No. 14,970

2 Claims. (Cl. 214—115)

1

This invention relates to novel and useful improvements in lifting and transporting apparatus.

An object of this invention is to lift a bale or other package and transport the same by improved means.

Another object of this invention is to frictionally engage the sides of a bale or the like, lift the same and transport it.

Another object of this invention is to provide a pair of rails by means of a suitable pivot on the tractor or prime mover, supply a plurality of tracks transversely of the rails and in slideable engagement therewith and also provide work engaging tines slideable in the said tracks.

Another object of this invention is to hydraulically actuate the said work engaging tools.

A still further purpose of this invention is to selectively control the actuation of the hydraulic actuation means.

Another object of this invention is to provide a generally improved lifting device for use in transporting bales, packages or other impedimenta.

Ancillary objects and features of novelty will become apparent to those skilled in the art, in following the description of the preferred form of the invention, illustrated in the accompanying drawings, wherein:

Figure 1 is an elevational side view of the preferred form of the invention;

Figure 2 is a schematic diagram of the hydraulic system utilized in association with the invention and forming a portion thereof;

Figure 3 is a sectional view of the lift means illustrated in Figure 1;

Figure 4 is a transverse sectional view of the detail of construction shown in Figure 3 and taken substantially on the line 4—4 thereof and in the direction of the arrows;

Figure 5 is a transverse sectional view taken on the line 5—5 of Figure 3 and in the direction of the arrows; and

Figure 6 is a longitudinal sectional view taken substantially on a line 6—6 of Figure 3 and in the direction of the arrows.

Referring now to the accompanying drawings, wherein like reference characters are used throughout to indicate similar elements, there is illustrated a device or apparatus which is characteristic of the present inventive concept. A conventional tractor or prime mover is generally indicated at 10 and provided with various and sundry appurtenances contiguous to and conventional to tractors or prime movers of this nature.

A pair of vertical rails having a channel-like cross-section are indicated at 12 and 14 respec-

2

tively and are connected by means of a head rail or header 16 at one pair of ends thereof. Fish plates 18 extend from the said rails 12 and 14 and have conventional pivot pins 20 interconnecting the rails with the chassis of the tractor 10. Means for pivotally actuating the rails 12 and 14 respectively may be provided if found desirable, this being a conventional fixture or apparatus.

Referring now primarily to Figures 3—5, there is illustrated a plurality of tracks 22, 24 and 26 respectively. These tracks are slidably received in the said channel-shaped rails 12 and 14 respectively through the expedient of the shoes 15 28 and 30. These shoes have an external configuration complementary to the internal dimensions of the channel-shaped rails and are slideable therein. The tracks are attached directly to the shoes and are vertically slideable therewith. Means for actuating the work engaging tines 32 and 34 respectively is provided. The preferable means may be seen best in Figure 3 wherein a pair of hydraulic rams 36 and 38 respectively including a pair of cylinders 35 and 37 having piston rods 40 and 42 are illustrated as being attached to the tines 32 and 34 by means of small brackets 44 and 46 respectively. These small brackets are integrally associated with the said tines as by welding, forming of a single cast, brazing or the like. The opposite ends of the rams are secured to alternate shoes 28 and 30, thereby rendering the rams slideable with the work engaging tines 32 and 34. Upon application of a force to the piston rods 40 and 42, the work engaging tines 32 and 34 will be actuated parallel to the tracks or transversely of the rails.

Means for raising and lowering the shoes and consequently the entire assemblage including the rams and work engaging tines is supplied. This means consists of a pair of plates 50 having pivot pins 52 associated therewith. Also secured to the said pivot pins is a telescopically adjustable shaft construction generally indicated at 54. This shaft construction terminates in a conventional transmission 56 which forms an operative portion of the conventional machine or tractor indicated at 10. Upon manipulation of the proper levers and handles and through conventional machinery, the plates 50 may be selectively raised and lowered.

The means for actuating the hydraulic rams may be seen best in Figures 1 and 2 wherein there is disclosed a pump 60 attached to the said tractor 10 and an oil reservoir 62 suitably located on the tractor. A filter 64 may be supplied 55 in the supply tank 62 to serve its usual and con-

ventional function and a line or conduit 66 connects the filter with the said pump 60.

Hydraulic fluid or the like is conducted through a flexible tube or conduit 68 over a sheave 70, thence to the inlet side of the hydraulic ram 38. Before extending over the sheave however, the conduit 68 extends to a four-way selector valve 71.

Interposed in the conduit or line 68 is a pressure relief valve 74 which has a return line 76 extending to the tank 62.

Following the diagram of Figure 2, it will be seen that fluid extends through the pipe or conduit 66 to the pump 60 from the said tank 62. Then, it extends through a suitable conduit to the overflow valve 74 then to the selector valve 71 and to the hydraulic ram 38. A second conduit 78 flexible in nature interconnects the second selector valve 80 for use in association with the second ram 36. Conduits 81 and 82 respectively extend from the selector valve 82 at both ends of the ram 38 for application of fluid to either side of the piston therein.

A conduit 86 extends from the selector valve 71 to one end of the said ram 38 while the said flexible conduit 68 extends through the other end. By manipulation of the four-way selector valves, fluid may be directed to either side of the pistons in the said rams or may be bypassed from the selector valve 71 to the selector valve 80 when it is found desirable. A return line 89 extends from the selector valve 80 to the tank 62 wherein the exhausted fluid is deposited for recirculation.

In summing up, each selector valve 71 and 80 may be manipulated to the positions of providing fluid to each end of the rams, to be bypassed from one selector valve to the other or may be set to the entirely closed position.

It will be noted from an inspection of Figure 2 that four flexible conductors are requisite for the desired manipulation and actuation of the work engaging tines 32 and 34 and therefore, four sheaves 70 are supplied on a common shaft 92. This common shaft extends between the rails 12 and 14, wherein it is journaled.

In journailling the said work engaging tines 32 and 34, inspection of Figure 6 discloses that a pair of shoes or runners 100 and 102 respectively are preferably rigidly secured to said work engaging tines and are fitted within the confines of the tracks. This permits the desired sliding movement and obviates undesired transverse movement relative to the desired travel of the work engaging tines.

Further, all of the rails 22, 24 and 26 may be interconnected by means of connecting rods 104 which form an operative portion of the said shoes 28 and 30. This expedient forms a carriage and is resorted to for smoothness in operation. Conventional levers 106 for steering of the vehicle and 108 for regulating the speed of the vehicle or tractor 10 as well as the stand 112 for supporting an individual are supplied in association with the conventional tractor 10 to serve their usual function. All other necessary appurtenances contiguous to such types of tractor are supplied in association with the tractor in order to render the same operative.

While there has been described and illustrated but a preferred form of the invention, it is apparent that variations may be made without departing from the spirit thereof. Accordingly, limitation is sought only in accordance with the scope of the following claims.

Having described the invention what is claimed as new is:

1. In a lifting and transporting apparatus, a tractor having a pump, a pair of vertical rails pivotally secured at their lower ends to said tractor, transverse tracks slidably secured in said rails, laterally movable work engaging tines slidably positioned in said transverse tracks, means for slidably actuating said tracks in said rails, means for slidably actuating said tines toward and away from each other, and means for communicating said last mentioned means with the pump, said tine actuation means comprising rams having pistons slidable in a direction perpendicular to said rails, said communicating means comprising a plurality of flexible conduits, a shaft journaled between said rails, sheaves on said shaft having said conduits positioned thereon, valves in said conduits for controlling the flow from the pump and rams.

2. A lift and transporting apparatus comprising a tractor having a pair of vertical rails pivotally attached at their lower ends thereto, transverse tracks extending between said rails, shoes vertically slidable in said rails and secured to said tracks, thereby mounting said tracks in said rails for vertical movement, means secured to one of said tracks and including an extensible shaft assembly for raising and lowering said tracks, work engaging tines slidable in said tracks longitudinally of said tracks, hydraulically actuating means for moving said tines toward and away from each other, control valves secured to said tractor for regulating said hydraulically actuating means, said actuating means including a pump on the tractor and rams, each ram including a cylinder with a piston therein, each piston having means connecting it to one of said tines, a header connecting the upper ends of said rails, a shaft journaled between said rails and having sheaves thereon, and flexible conduits intercommunicating said rams and said pump and locating on said sheaves.

LOUIE H. PONNEQUIN.
